(57) **CLAIM**

The ornamental design for an eyeglasses clip, as shown and described.

DESCRIPTION

FIG. 1 is a rear perspective view of an eyeglasses clip showing our my new design, in an environment of use;

FIG. 2 is a front perspective view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken line portion of the figure drawings is included to show unclaimed subject matter only and forms no part of the claimed design.
